GEARING FOR WASHING-MACHINES.

1,157,474.

Specification of Letters Patent.

Patented Oct. 19, 1915.

Application filed November 17, 1913. Serial No. 801,378.

To all whom it may concern:

Be it known that I, ORLA H. WATKINS, a citizen of the United States, and resident of Clinton, in the county of Clinton, State of 5 Iowa, have invented new and useful Improvements in Gearing for Washing-Machines, of which the following is a description, reference being had to the accompanying drawings, which are a part of this specification.

My invention has relation to improvements in Gearing for washing machines, more especially to washing machines adapted to be run by an electric, or other suitable 15 form of motor.

The invention is designed to provide a gearing device of simple, durable and inexpensive construction, especially designed for use in operating washing machines and 20 wringers by means of power applied by an electric motor or other source of power.

The invention further is designed to provide a new and improved form of gearing device.

25 With the above and other incidental objects in view, the invention consists of the devices and parts, or the equivalents thereof, as hereinafter more fully set forth.

In the accompanying drawings, Figure 1 30 is an elevation of the gearing device, parts being shown in section; Fig. 2 is a plan view of the gearing as applied to the machine; Fig. 3 is a fragmental end view; Fig. 4 is an elevation showing the top or cover of the 35 tub closed, and also showing the detachable clothes chute in position, and further showing said chute in longitudinal section, and the wringer in vertical section.

Referring to the drawings, the numeral 5 40 indicates the tub of the washer, which is of the usual upwardly tapering form. This tub is preferably supported on legs 6, and in the lower ends of these legs are preferably mounted casters (not shown), to provide for the easy and convenient moving of the washing machine from one place to another.

At the upper edge of the rear of the tub 5, and against the inner side of the wall thereof, is a block 7. To the upper surface 45 of this block is secured by means of bolts 8,

a ledge 9, said ledge extending over the top edge of the tub, and outwardly for a desired distance. Bolted to, and extending longitudinally of, this ledge 9, is a casting 10, said casting being formed or provided with 55 upstanding bearings 11-11 for a longitudinal shaft 12. The said shaft is provided on one of its ends with a large belt pulley 13, and upon its opposite end with a beveled pinion 14, and intermediate of its ends is 60 formed with a worm 15. A belt 16 passes around pulley 13, and is then extended downwardly and around a small pulley 17. On the end of a shaft 18 is an ordinary form of electric motor 19, the said electric motor 65 being supported on a suitable ledge or support (not shown) beneath the tub.

The top or cover of the tub is indicated by the numeral 20, and the inner straight edge of said top or cover, when in closed position, abuts against the inner straight edge of 70 the ledge 9.

The hinge connection for the top or cover may be of any desired form. I show in the drawings a hinge construction which I prefer to use, and which consists of two plates 21-21 secured to the top, or cover, and having their rear ends extended upwardly and rearwardly at an inclination. The extremities of these rearward extensions are 75 provided with openings to receive freely therethrough hinge pins 22-22, which pins extend from upwardly projecting ears 23-23, which ears project from the bearings 11-11. The top or cover, when lifted 80 or turned down, is, therefore, turnable upon the hinge pins 22. Also connected to the upper side of the top or cover is a plate 24, and projecting upwardly from this plate is a stud 25. The numeral 26 indicates a worm 90 wheel which is in mesh with the worm 15 of shaft 12. The under side of this worm wheel is provided with a hub 27 which loosely surrounds the stud 25, the lower end of said hub resting and rotating upon the annular 95 shoulder 28 formed on the stud near the lower end of said stud. The plate 24 has also projecting outwardly from its rear end a tongue 29, which tongue, when the top or cover is turned downwardly to a closing po- 100

sition, is adapted to engage with a keeper or pocket 30, preferably integral with, and extending inwardly from, the casting 11. By thus providing for the engagement of this 5 tongue with the keeper or pocket referred to, the worm wheel 26 is made to properly mesh with the worm 15, when the cover is in closed position, notwithstanding any slight displacements of parts which might occur, 10 due to warping, or other causes.

The numeral 31 indicates a horizontally rocking or turntable agitating device within the tub. This device may be of any desired form, but I prefer to employ the form illustrated in the accompanying drawing, in which the said agitator is shown as consisting of a disk-like member having a series of downwardly diverging arms or fingers depending from the under side thereof. The 15 shaft of this agitator is indicated by the numeral 32. This portion of the agitator is preferably rotatable with, but vertically movable upon, the shaft. This function is procured by providing the shaft 32 longitudinally thereof, and at diametrically opposite points, with wings 33—33, said wings adapted to fit within lateral branch slots 34—34 from the central shaft opening of the disk. The shaft 32 passes loosely through 20 the opening of the disk, and the lower end of the shaft is provided with a head bearing against the under side of the disk, to prevent the said disk from dropping entirely off the shaft. When the shaft is rotated, it is obvious that, by reason of the provision of the 25 wings 33 fitting in the lateral branch slots 34, the agitating device must necessarily be rotated with the shaft, and if there is any pressure exerted against the under side of 30 the agitating device by the contents of the tub, the said device is capable of moving upwardly on the shaft, and thus be relieved of such pressure.

The upper end of shaft 32 which passes 35 through the top or cover, is slightly reduced, and carries at its upper end a short crank 35. This short crank is preferably mounted just above a central plate 36 secured to the center of the upper side of the top or cover. 40 This plate has extending upwardly therefrom a pivot stud 37, which is surrounded by the depending hub 38 of an upper longer crank 39. The under side of this crank 39 is provided with an elongated recess 40. 45 The end of short crank 35 is provided with an upwardly-extending pin 41, which pin carries an anti-friction roller 42, which roller fits within the recess 40 on the under side of the long crank 39 and bears against 50 the side walls of said recess.

Pivottally connected at one of its ends to the outer end, of the long crank arm 39, is a pitman 43. The opposite end of this pitman is pivotally connected to the worm-

wheel 26. It will be evident that with the use of the described gearing and the crank connections, when the shaft 12 is rotated, a reciprocating movement will be imparted to the pitman, and this will have the effect of turning the long crank arm 39 a quarter turn, first in one direction, and then in the other. As the end of the short crank arm works in the elongated recess 40 of the long crank arm, it is evident that with the swinging of said long crank arm, the short arm is given a half turn in opposite directions, and this, in turn, will cause the shaft 32 and its agitating device, to be correspondingly rocked or turned a half turn with every quarter turn of the long crank arm. It is important for the effective agitation of the clothes within the tub, that the agitator be given a half turn in both directions, and it is through the provision of the novel arrangement of the crank connection just described, that I am able to accomplish this.

The wringer attachment, which is of the ordinary construction, is designated in the drawing by the numeral 44, and is located at one end of the machine, being mounted on an outstanding ledge or horizontal support 45. Corresponding ends of the shafts 46—46 of the wringer rolls, are geared together in the usual manner, the gears not being shown. The lower wringer-roll shaft 46 carries on its extreme end a gear wheel 47 which meshes with an idler gear 46' mounted on a pin or stud, and which gear 46' is in mesh with a wider gear 48, mounted fast on a transverse shaft 49. This shaft 49 is 100 slidable longitudinally in its bearings, and at one end thereof carries fast thereon two crown gears 50—50, said crown gears being spaced a suitable distance apart, and being covered and protected by a protecting hood 105 51. The crown gears are so located on shaft 49 that the beveled pinion 14 is in a position between said gears. In Fig. 2 of the drawings, the beveled pinion 14 is shown in mesh with the outer crown gear 50, and consequently, when the motor is connected up 110 to cause the rotation of shaft 12, the said rotation is imparted to the outer crown gear 50 through the intermeshing therewith of the beveled pinion 14. As the crown gear 115 is fast on shaft 49, said shaft is necessarily rotated in one direction, and this rotation of shaft 49 will cause, through the intermeshing gears 48 and 46'—47, the rotation of the shaft 46 of the lower wringer-roll, 120 (the latter being designated by the numeral 52), and the consequent rotation of the wringer-rolls in a direction to cause the clothes passed therebetween to be moved in one direction. Now, if it is desired to 125 cause the wringer-rolls to rotate in a direction opposite to the first described rotation, so as to feed the clothes passed therebetween

in an opposite direction, to the direction first referred to, the shaft 49 is shifted longitudinally, or pushed in a direction toward the left of Fig. 2. This will have the effect of bringing the inner crown-wheel 50 into engagement with the beveled pinion 14, with the necessary result that the opposite rotation referred to, must take place. The fact that the gear 48 is wider than the gear 46', which is in mesh therewith, admits of a continuation of the internmeshing relation of the gears, notwithstanding the shifting of the shaft 49. When it is desired to throw the wringer mechanism entirely out of operation, all that is necessary to be done is, to shift the shaft 49 to such position that the beveled pinion 14 will lie intermediate of the two crown gears and out of meshing engagement with both.

The shifting of shaft 49 may be accomplished in any desirable manner, but I prefer to employ for the purpose a wringer lever 53. The inner end of this lever is sleeved on the shaft 49, the inner end of said sleeve bearing against the hub of the gear 48. This sleeved end of the lever is provided with a worm thread 54, which is adapted to work in a diagonally disposed groove 54', formed at the upper end of an upstanding lug 54''. By turning the lever in one direction the worm thread, by reason of its engagement with the groove referred to, causes shaft 49 to shift longitudinally in one direction, and by turning the lever in the opposite direction, the said longitudinal shaft is caused to shift in the opposite direction.

In order to protect the gears 47-46' and 48 from clogging matter, I prefer to cover the same with a removable hood 61. I also prefer to cover and protect the different parts which are mounted upon the top or cover of the main tub 5, viz., the worm wheel 26, pitman 43, cranks 35 and 39, and related parts, and for this purpose I employ a hinged cover 62.

From the above description it is thought that an extended explanation of the operation of the machine, will be unnecessary. Of course, where an electric motor is employed, the said motor is connected up to an ordinary electric light socket in the usual way, or, when any other form of motor is employed, it is connected up to the source of power. It will be assumed that the tub 5 is filled with water and clothes, and the top or cover 20 of said tub is closed, and the shaft 49 is adjusted longitudinally to such position that the beveled pinion 14 occupies a non-meshing intermediate position between the two crown gears 50. When power is turned on, necessarily the agitating device will be caused to be rocked or turned back and forth a half turn in both direc-

tions, whereby the clothes within the tub 65 are given a thorough agitation and consequent cleansing. After the clothes have been agitated for the required time to insure thorough cleansing, the top or cover and the parts carried thereby, are raised to the dotted line position shown in Fig. 1. This necessarily will carry the worm-wheel 26 out of meshing engagement with the worm 15, and consequently, the operation of the agitator will be stopped, and this without the necessity of turning off the power. The clothes are now lifted from the main tub 5 and raised sufficiently to cause their engagement by the wringer rolls. The shaft 49 is next shifted so as to cause one of the crown 80 gears 50 to engage the beveled pinion 14. The particular crown gear thus made to engage the pinion 14, is the one which will cause rotation of the wringer rolls in a direction to compel an outward movement of 85 the clothes and the deposit of the clothes into a rinsing tub located adjacent to the wringer. After all the clothes have thus been taken from tub 5 and deposited in the rinsing tub, tub 5 can then be again filled 90 with clothes and the top or cover thereof turned downwardly, so as to again bring the worm gearing into mesh, and cause the agitating device to operate. After the clothes have remained in the rinsing tub for the 95 proper time to insure complete rinsing, they are removed from said tub and after being passed through the wringer rolls are placed in a bluing tub which is set in the place formerly occupied by the rinsing tub adjacent to the wringer. The clothes chute 63 is now adjusted to the position shown in Fig. 4, and the shaft 49 is shifted, so as to cause its other crown gear 50 to engage the beveled pinion 14, to thereby cause a reverse or inward action of the wringer-rolls.

The invention thus exemplifies an improved gearing device which is more particularly applicable to a washing machine.

The invention is not to be restricted to the 110 details of construction herein set forth but may be varied so as to be within the scope of the appended claims.

What I claim is:

A gearing device comprising a fixed support, a supporting member hinged to said support, a power shaft on the fixed support, a worm on said shaft, a gear wheel rotatably mounted on the hinged supporting member and in mesh with said worm, a notched plate on the fixed support adjacent the worm, a tongue on the hinged member adjacent the gear, said tongue and notch co-operating to align the worm and wheel when the hinged member is in closed position, an upright shaft journaled in the hinged supporting member, a lever pivotally secured to the hinged member and having a

recess therein, a crank mounted on the upright shaft and slidably and pivotally connected to said lever within the recess thereof, a pitman pivotally connected to said 5 gear wheel and lever whereby the continuous rotation of the power shaft will horizontally reciprocate said upright shaft.

In testimony whereof, I affix my signature, in presence of two witnesses.

ORLA H. WATKINS.
